UNITED STATES PATENT OFFICE.

CHARLES J. KINDEL AND JOHN B. ANDRES, OF NEW YORK, N. Y., ASSIGNEES TO KINDEL SOMERSAULTIC DAVENPORT COMPANY OF DELAWARE.

DAVENPORT-BED.

No. 393,522.

Specification of Letters Patent.

Patented July 14, 1903.

Application filed September 23, 1907. Serial No. 394,141.

To all whom it may concern:

Be it known that we, CHARLES J. KINDEL and JOHN B. ANDRES, citizens of the United States, and residents of New York city, county of New York, and State of New York, have invented new and useful Improvements in Davenport-Beds, of which the following is a specification.

This invention relates to davenport beds and particularly to those wherein the back is transferable to a horizontal position in front of the seat, when the davenport is to be converted into bed form, and turns a somersault in transit.

15 The object of the invention is to make certain improvements in details of construction, especially in the legs for supporting the front edge of the back when the davenport is in bed form, also in the manner of attaching the bedding box to the ends of the davenport and in the structure and hanging of the davenport seat whereby to make the bedding box readily accessible.

20 To this end the invention consists in the construction and combination of parts practically in the form and manner hereinafter described and claimed.

In the accompanying drawings, which constitute a part of this specification, Figure 1 25 represents, in end elevation, the back, seat and bedding box of the improved davenport, disclosing the link mechanism for effecting the transfer of the back from one position to the other and the means for attaching the several parts to the end pieces of the davenport, said end pieces being indicated by 30 broken lines and the bed form of the davenport being indicated in dotted lines. Fig. 2

35 represents, in vertical section, the manner of attachment for the legs which support the front edge of the back when the davenport is in bed form. Fig. 3 represents a plan of the link mechanism when the davenport is in bed form. Fig. 4 is an end elevation of the back and seat of the davenport showing modifications in the attachment of the movable legs for the front of the bed and also a stop and guides for the link mechanism. Fig. 5 represents, in vertical section on line 5-5, Fig. 4,

40 one end of the davenport with the link mechanism of Fig. 4, the bedding box of Fig. 1 and the seat of Fig. 6. Fig. 6 represents a vertical section through the seat and bedding box seen in Fig. 5, the view being towards the 45 end opposite to that shown in Fig. 5, as indi-

cated by the darts on line 6-6. Fig. 7 represents in elevation, vertical section and transverse section, the clip for attaching the bedding box to the ends of the davenport. Fig. 8 represents, on an enlarged scale and in 50 longitudinal section, the modified leg seen in Fig. 4.

55 In the drawings 8 refers to the end pieces which are preferably united by the bedding box indicated by 9. Supported upon and attached to this box is the seat portion 10 of the davenport, and at 11 is the back portion of the davenport, while the legs for supporting the front edge of the back, when in bed form, are represented at 12. The links uniting the back to the end pieces 8 are indicated at 13 and 14 respectively, the latter being curved so as to form pillow holders.

60 The davenport is preferably so constructed that it may be shipped in knock-down condition; therefore, box 9 is removably connected to ends 8 in any suitable detachable manner. This may be done in many ways. In the structure shown, the ends of the box are made to abut squarely against the ends 8 and the end boards 15 are set in from the ends of the bottom and sides of the box and, in the recess between the end boards 15 and the ends 8, are attached, near each edge of ends 8, the clips 16. These clips consist of 65 curved plates, each notched at the upper end to receive the shank of a bolt 17, whose polygonal head rests in the hollow of the plate. These bolts pass through the end boards 15 and receive thumb-nuts 18. By 70 means of these plates and bolts the ends 8 and box 9, constituting the real frame of the davenport, are readily assembled.

75 The seat 10 may be of any desired construction, but it and also the back 11 are 75 preferably upholstered bodies provided with spiral springs as indicated in the seat in Fig. 6. One practical way for detachably connecting the seat to the frame is indicated in Figs. 5 and 6. To the base frame of the seat, at each end, is riveted a bracket 19 and to the upper end of each of these brackets is pivoted a support, 20, which passes down through a strap 21, attached to each end board 15, and straddles, by a notched end, a pin or screw 80 85 projecting from the end board.

90 The back 11 is attached to the frame by the links 13 and 14. These may be connected directly to the end pieces 8 and to the ends of the back 11, but preferably are pivoted to 95 100 105 the end pieces 8.

bars 22 and 23, provided with bolt or screw holes, and readily attachable, respectively, to the ends 8 and the back 11, as clearly indicated in Fig. 3; said bars being let into their respective parts to lessen the space between the back and end pieces.

To bring the legs 12 into proper position for supporting the front edge of the back, when in bed form, and to have them concealed when the davenport is in settee form, they may be constructed as seen in Figs. 1 and 2. Therein they are shown of substantial thickness and have a reduced upper end by which they are pivoted on the same pivot as that connecting the swinging end of link 14 to the back. This reduced end projects beyond the pivot and is provided with a transverse slot in which plays a stud projecting from the link 14 as seen at 24. This slot allows of sufficient play for the leg to take its position behind link 13 when the davenport is in settee form and also to take the vertical, supporting position when the davenport is in bed form. To insure against the foot of the leg swinging out too far in the latter position, a stop as 25 may be placed on the back 11. Instead of prolonging the leg beyond its pivot the link 14 may be prolonged and slotted and the pin put in the leg as indicated in Figs. 4 and 8.

To provide against the curved link 14 catching on the end of link 13 when starting the back forward in the conversion of the davenport into a bed, the lower end of link 13 may be produced as indicated in Fig. 1, or guides as 26 may be attached to the ends 8 under the lower ends of links 13 as seen in Figs. 4 and 5. By curving the links 13 so that they will rest against the legs 12 at the pivot of the latter, a back-stop for the back 11 is provided but, in addition to this, or to serve alone for this purpose, a stop as 27 may be attached to each end 8 to be engaged by the link 14.

In order to provide a capacious bedding box and to provide for ready access thereto without detracting from the width or appearance of the seat, it is essential to so construct the seat and to so hinge it that it may be swung up easily and without interfering with the back or with the contents of the box. Therefore, the hinge must be as near as possible to the front lower corner of the back, see Fig. 6, then there will be no binding or rubbing between the seat and back in swinging up the former to open the box. Then to prevent the rear edge of the seat from swinging down into the box, the rear lower corner of the seat must be dispensed with. This may be done by making the base frame of the seat narrower and replacing the last row of vertical spiral springs by springs in which the spirals are horizontal, substantially as indicated at 28.

To prevent the link mechanisms and swing-

ing legs from marring the parts between which they pass in the transformation of the davenport, suitable buffers may be employed. The legs 12 may be wrapped in some suitable fabric, or they may have set into a cavity therein a piece of wood wrapped with fabric, as indicated at 29 in Figs. 4 and 8. A buffer consisting of a tapering block may also be wrapped with fabric and attached to each link 14, as indicated at 30 in Figs. 4 and 8, thereby to avoid any possibility of the upper ends of legs 12 striking the end pieces 8 as the back 11 is swung into settee position.

The invention claimed is:

1. In a davenport having a transferable back connected in place by links, the combination with the links, of a leg at each end of the davenport, for supporting the forward edge of the back when in bed form, pivoted to the link connecting the lower edge of the back to the frame of the davenport and at the same side of said link as is the link connecting the upper edge of the back to the frame of the davenport, whereby to save space and to take its place behind the latter link when the davenport is in settee form.

2. In a davenport having a transferable back, the combination of a link at either end of the davenport connecting the lower edge of the back to the frame of the davenport, a link at either end of the davenport connecting the upper edge of the back to the frame of the davenport, and a leg at either end of the davenport pivoted to the link connected to the lower edge of the back and at the same side of said link as is the link connected to the upper edge of the back, thereby being in position between the back and the end of the davenport and taking its place behind the latter link when the davenport is in bed form, said legs being also provided with buffers whereby to prevent marring or wearing the parts touched by them.

3. In a davenport, whose back is adapted to take a horizontal position when the davenport is in bed form, the combination with the back, of links connecting it to the body of the davenport, legs, one at each end of the back, for supporting the free edge thereof when in bed form, each leg being pivoted to the back by the same pivot as is one of said links, and a pin-and-slot connection between the leg and its respective link at one side longitudinally of said pivot, whereby the leg is directed and its movement limited as the back is moved into either of its positions of rest.

4. The combination with the end pieces of a davenport, of a bedding box serving as the part of the frame which connects together the end pieces of the davenport and having its sides projecting beyond the ends thereof to form a space between the said ends and the end pieces of the davenport, clips attached to the end pieces of the davenport within these

spaces, and bolts passing through the ends of the box and having heads removably fitted to said clips, for the purpose set forth.

5. The combination with a bedding box and seat, of straps secured to the ends of the box, supports pivoted to the seat and notched at their lower ends, and projections near the bottom of the box to be straddled by the ends of said supports after the latter 10 have been passed down through the straps.

6. The combination with a bedding box, of an upholstered seat cut away at its rear lower edge, and supports attached to the ends of the box and pivoted to the seat near 15 its upper surface and at the inner edge of the cutaway portion.

7. In a davenport, the combination with the back, of a bedding box, a seat forming a 20 cover to the bedding box, and extending under the lower edge of the back and having this portion cut away along its lower edge, brackets attached to said seat and provided with pivots near the forward lower edge of the back, and a row of vertically disposed 25 springs having horizontal spirals located in the edge whose lower portion is cut away, for the purpose set forth.

8. In a davenport, the combination with a 20 back, of a bedding box, a seat forming a one-piece cover to the bedding box and extending under the lower edge of the back, and hinge pivots located adjacent to the lower forward edge of the back, but independently

thereof for connecting the seat to the frame of the davenport.

9. In a davenport, the combination with a back, of a bedding box, a seat forming a cover to the bedding box, and extending under the lower edge of the back and having this portion cut away along its lower edge, 40 and brackets attached to said seat and provided with pivots near the forward lower edge of the back.

10. In a davenport having a transferable back, the combination with the links connected to the lower edge of the back and curved to form pillow supports and the links connected to the upper edge of the back, of 45 guides for directing the curved, pillow-supporting links past the pivotal points of the 50 other links.

11. In a davenport having a transferable back, the combination with curved, pillow-supporting links of the links pivoted to the upper edge of the back and prolonged beyond their other pivotal point, thereby to 55 lap onto the curved links and guide them beyond the said other pivotal points.

In testimony whereof we have signed our names to this specification in the presence of 60 two subscribing witnesses.
